CLAIM

We claim the ornamental design for an information handling system, as shown and described.

DESCRIPTION

FIG. 1 is a front perspective view of the information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom rear perspective view thereof;

FIG. 9 is a front right side perspective view;

FIG. 10 is a top right side perspective view;

FIG. 11 a front perspective view of the information handling system coupled to the rear side of a display in an environment of use; and,

FIG. 12 is a front perspective view of the information handling system coupled to the rear side of an alternative display in an alternative environment of use.

Broken lines showing a Display in FIGS. 11-12 depict unclaimed environment and form no part of the claimed design. The unshaded surface adjacent to the broken line seen in FIGS. 3 and 8 forms no part of the claimed design. All other broken lines depict portions of the information handling system that form no part of the claimed design.
